UNITED STATES PATENT OFFICE.

W. FRANK BROWN, OF HIGH POINT, NORTH CAROLINA.

COMBINED ASH PAN AND SIFTER.

1,253,780.

Specification of Letters Patent. Patented Jan. 15, 1918.

Application filed April 28, 1916. Serial No. 94,167.

To all whom it may concern:

Be it known that I, W. FRANK BROWN, a citizen of the United States, residing at High Point, in the county of Guilford and 5 State of North Carolina, have invented certain new and useful Improvements in Combined Ash Pans and Sifters; and I do hereby declare the following to be a full, clear, and exact description of the invention, such 10 as will enable others skilled in the art to which it appertains to make and use the same.

This invention relates to a combined ash pan and sifter, designed to be placed beneath the grate of a fire place for receiving the ashes and unconsumed portions of fuel which pass below the grate, and the object of the invention is to improve the general construction of such devices so that the same 20 will be of simple and durable construction, efficient in operation, can be adjusted to accommodate fire places of different sizes and will admit of the sifting section being conveniently detached from operative position 25 so as to admit of the unconsumed portion of the fuel, located therewithin, being emptied into a suitable receptacle or into the grate.

Other objects will appear and be better understood from that embodiment of my 30 invention of which the following is a specification, reference being had to the accompanying drawing forming a part thereof, in which:

Figure 1 is a top plan view of the combined ash pan and sifter removed from the fire place.

Fig. 2 is a transverse sectional view, taken through the fire place and through the ash pan, and showing the ash pan in operative 40 position, and

Fig. 3 is a vertical sectional view, taken through the combined ash pan and sifter.

Fig. 4 is a detail section taken through the upper end of one of the side walls of a 45 modified form of ash receiving and sifting device.

Referring to the drawing in detail, the letter A designates a fire place, having the usual inwardly converging walls B.

50 The combined ash pan and sifter is shown as consisting of an ash-receiving section 1 and a sifting section 2. The section 1 is of rectangular configuration, having a bottom wall 3, opposite side walls 4 and end walls 5. The upper ends of the side walls 4 of 55 the section 1 are bent to provide horizon-

tally disposed flanges 6, and the terminals of the walls are extended upwardly at obtuse angles to the flanges 6, as shown at 7, and then bent upon themselves to provide portions 8 which overlie the portions 7 and then extended horizontally to provide a flange 9, which lies above and in spaced relation with the flanges 6.

Mounted on the upper edges of the end 65 walls 5, of the section 1, are slidable extensions 10. Each of these extensions consists of an elongated flat plate having its inner longitudinal edge provided with spaced slits 11, and the portion between the slits is bent 70 downwardly to provide a tongue 12. The inner edges of the end portions of the plate are extended beneath the flanges 6 and 9, and the extremities of the plate are bent upwardly, as shown at 13, and received by the 75 space between the portions 7 and 8 and the side walls 4 of the section 1. The outer longitudinal edge of the plate is also bent upward, as shown at 14, and owing to the upwardly extending portion 7 on the side 80 walls 4 and the upwardly bent edges 14 of the extensions or plate 10, a suitable guard will be provided for preventing the ashes from falling on the outside of the section 1. By virtue of the provision of the slidable 85 extension 10, the section 1 can be adjusted to different lengths so as to accommodate fire places of different sizes, outward movement of the extension being limited by engagement between the tongues 12 and the 90 end walls 5 of the section 1. Also by the particular connection between the extensions and the section 1 the extensions can be adjusted to different angular positions, as shown in dotted lines, so as to admit of the 95 extensions being positioned in engagement with the side walls of the fire place and prevent any of the fuel and ashes dropping between the section 1 and the walls of the fire place.

100 Mounted on the inner surfaces of the opposed side walls 4 of the section 1 and at opposite points are a pair of U-shaped hooks 15. These hooks 15 admit of suitable tools being attached to the receptacle 1 so as to 105 provide means for lifting the pan.

The sifting section 2 comprises a rectangular piece of foraminous material 16, having its marginal edges secured within a frame 17. The frame 17 consists of a metal 110 strip bent upon itself to provide clamping portions between which the foraminous ma-

material is clamped and the sides and end portions of the frame are bent upwardly, as shown at 18, to provide a guard for preventing any of the material deposited thereon 5 from falling over the sides or ends of the section 2 when the latter is removed.

Upon referring to Fig. 3, it will be seen that when the sifting section 2 is in operative position the frame 17 is supported by 10 the flanges 6 and the upwardly extending portions 7 on the side walls 4 of the lower section 1.

When the ashes and unconsumed parts of the fuel drop onto the foraminous material 15 16, and the ashes are liberated from the fuel and dropped into the section 1, the sifting section 2 can be removed from the section 1 and the fuel thereon emptied into a suitable receptacle, or into the grate of the fire place. 20 When the section 1 has been filled with ashes, and the sifting section 2 removed suitable tools, not shown, can be forced downward in the body of the ashes within the section 1 so as to engage the hook members 15 to admit of the section 1 being lifted or carried to 25 a point where it is desired to deposit the collected ashes. The said tools for removing the section 1 can be in the nature of pokers.

In the modification shown in Fig. 4 instead of first bending the upper ends of the side walls horizontally, as shown at 6, in Fig. 3, and then forming the angular flanges 7, the said flanges are connected directly to the upper ends of the side walls 4 of the 35 lower section 1. In this construction the foraminous material forming the sifting section 2 has its marginal edges bent upwardly to provide flanges 19, and a reinforcing frame 20 extends around the free edges of the angular portions 19, and rests upon the flanges 7.

Having thus described my invention what I claim as new, is:

1. A device of the class described comprising an ash-receiving receptacle having bottom, side and end walls, the upper edges of the side walls being bent outwardly and upwardly and then terminally bent inwardly in spaced relation to the outwardly and upwardly bent portions so as to define guides, 45

an ash sifter overlying the ash receptacle and consisting of a piece of foraminous material and a frame overlying and resting on the inwardly bent terminals of the upper edges of the sides and formed of a strip of metal 55 bent to provide clamping portions for receiving the marginal edges of the foraminous material, and an upwardly extending portion to provide a guard, for the purpose specified. 60

2. A device of the class described comprising an ash-receiving receptacle having bottom, side and end walls, guides formed on the upper edges of the side walls and extending throughout the length of the side 65 walls, an ash sifter overlying the ash-receiving receptacle and resting on the guides, extensions located at the upper ends of the end walls of the ash-receiving receptacle and having portions slidably received by the 70 guides and adapted for outward longitudinal adjustment with respect to the ash-receiving receptacle and the ash sifter, and means carried by the extensions for engaging the end walls for limiting the outward 75 adjustment of the extensions.

3. A device of the class described comprising an ash receptacle having side and end walls, the upper edges of the side walls being bent outwardly and upwardly and 80 terminally bent to provide guides, an ash sifter overlying the ash receiving receptacle, and extensions located at the upper edges of the end walls of the ash-receiving receptacle and each consisting of a rectangular body 85 portion adjustably received by the guides and having a depending tongue formed on one of the longitudinal edges thereof for engaging the adjacent end walls of the ash-receiving receptacle, when the sections are 90 moved in one direction, so as to limit the movement of the extensions in the mentioned direction.

In testimony whereof I affix my signature in presence of two witnesses.

W. FRANK BROWN.
